[57] **CLAIM**

The ornamental design for a box for baby teeth, as
shown and described.

DESCRIPTION

FIG. 1 is a front elevational view of a box for baby teeth
showing our new design;
FIG. 2 is a right side elevational view thereof;
FIG. 3 is a left side elevational view thereof;
FIG. 4 is a rear side elevational view thereof;
FIG. 5 is a bottom plan view thereof; the top plan view
being a mirror image thereof;
FIG. 6 is a front elevational view thereof, with the box
lid shown in an open condition;
FIG. 7 is a top plan view of FIG. 6;
FIG. 8 is a rear elevational view of the insert; shown for
clarity of illustration;
FIG. 9 is a right side elevational view of FIG. 8;
FIG. 10 is a top plan view of FIG. 8; and,
FIG. 11 is an exploded perspective view thereof; with
the insert taken out of the box; shown for clarity of
illustration.
